MASS SPECTROMETRY

Thomas E. Usher, Scotia, and George Jernakoff, Schenectady, N. Y., assignors to General Electric Company, a corporation of New York

Application September 24, 1952, Serial No. 311,199

8 Claims. (Cl. 250—41.9)

This invention relates generally to mass spectrometry and, more particularly, to methods and apparatus for stabilizing the sensitivity of the measurement of ions according to mass-to-charge ratio.

This application is a continuation in part of our pending application Serial No. 302,724, filed August 5, 1952, and assigned to the assignee of the present application.

Mass spectrometry can be defined as the art of analyzing a gas or vapor by ionizing molecules of the gas or vapor, separating the ions according to mass-to-charge ratio and selectively measuring the separated ions. Mass spectrometry is employed as a means of determining qualitatively and quantitatively the constituents of a vapor or gas, or a mixture of vapors or gases, and as a means of measuring the isotope abundance ratios of the elements.

Several forms of mass spectrometer apparatus have been evolved to enable the practice of mass spectrometry. All such apparatus are characterized by certain common elements which are required to perform the desired analyses. For example, all mass spectrometer apparatus include sample reservoirs from which the gases of vapors undergoing analyses are admitted through a leak to the apparatus for ionization and separation according to mass-to-charge ratio. And since a vacuum must be maintained within the regions of ionization and ion separation, the several forms of mass spectrometer apparatus also include a vacuum pump system for continuously evacuating such regions of the apparatus.

We have found that the effect of the aforementioned common elements of mass spectrometer apparatus can produce deleterious operational characteristics. Thus in the operation and utilization of mass spectrometer apparatus, unless the sensitivity of the apparatus is essentially independent of the pressure at which a sample is admitted, the speed of evacuation and the ultimate pressure to which the evacuable portions of the apparatus can be evacuated, the sensitivity varies greatly due to normal changes in the elements which determine such factors. As employed herein, "sensitivity" is defined as the amount of measured ion current, representing selectively separated ions, per unit of pressure of the admitted sample of gas or vapor. Since the magnitude of the measured ion current is the basis for the quantitative determination of the constituents of a sample, it therefore is apparent that sensitivity variations obviate the attainment of fully accurate analyses.

According to the present invention sensitivity variations from the above-described causes are minimized or essentially eliminated by making the sensitivity of mass spectrometer apparatus substantially independent of changes in sample, pressure, speed of evacuation and ultimate pressure. This is accomplished by providing certain specified interrelationships among the speed of evacuation, sample pressure, ultimate pressure, and flow conductances of the apparatus.

The features of the invention desired to be protected are set forth in the appended claims. The invention itself, together with further objects and advantages thereof, may best be understood by reference to the following specification taken in connection with the accompanying drawings in which Fig. 1 is a simplified schematic view, partially in section, of mass spectrometer apparatus according to the invention; Fig. 2 is a partly schematic view of an alternative flow construction which can be employed in the apparatus of Fig. 1; and Fig. 3 is a

2

simplified section view of a portion of a mass spectrometer tube which can be utilized in connection with certain of the apparatus of Fig. 1 according to the invention.

Referring particularly now to Fig. 1 there is shown in simplified schematic fashion mass spectrometer apparatus according to the invention. The apparatus comprises a mass spectrometer tube 1 which can be continuously evacuated through a pump connection 2 by means of a diffusion pump 3 and a mechanical rough vacuum pump 4. Diffusion pump 3 and rough pump 4 can be of conventional, commercially available types well known to those familiar with vacuum techniques. A vapor trap 5 is provided in the pump connection 2 between mass spectrometer tube 1 and diffusion pump 3 for the purpose of removing condensable vapors from the vacuum system. Vapor trap 5 is partially surrounded by a cooling medium 6, such as liquid nitrogen or air, contained within an insulated vacuum flask 7.

Mass spectrometer tube 1 can be any one of the several types known heretofore. For example, tube 1 can be of the type disclosed in U. S. Patent No. 2,535,032, issued to Willard H. Bennett on December 26, 1950, wherein ions are separated according to mass-to-charge ratio by a plurality of linearly arranged unidirectional and radio frequency potentials. Alternatively, tube 1 can be of the form disclosed in U. S. Patent No. 2,570,158, issued to Paul O. Schissel on October 2, 1951, and assigned to the assignee of the present invention. In the Schissel tube, ions formed therein are accelerated by means of an alternating electric field against the force of an electrostatic or direct current electric field having a linear space distribution, whereby the ions become separated in space according to mass-to-charge ratio. Also tube 1 can be as shown and described by Robert V. Langmuir in U. S. patent application Serial No. 669,044, filed May 11, 1946, and assigned to the assignee of the present invention. In the Langmuir tube ions are accelerated in spiral paths by an alternating electric field in the presence of a magnetic field, whereby ions having a natural frequency corresponding to the frequency of the alternating electric field are spatially separated from the remaining ions. As yet another alternative, tube 1 can be of the type disclosed by Gaylord W. Penney in U. S. Patent No. 2,581,813, issued January 8, 1952, wherein ions are separated according to mass-to-charge ratio by a divergent alternating electric field and a magnetic field. That still other forms of mass spectrometer tubes may be employed will be apparent as the description of the present invention proceeds.

Vapors or gases to be analyzed within mass spectrometer tube 1 are admitted from a sample reservoir 8 through a leak 9 which can consist of a diaphragm of thin metal foil having minute holes therethrough. The metal foil is sealed about its periphery to a tubular connection 10 between reservoir 8 and tube 1 as illustrated. To assure desired ionization of admitted samples, connection 10 preferably extends within tube 1 to an ionization chamber 10' which is diagrammatically illustrated by the dotted lines. The vapors or gases admitted to tube 1 are ionized by electron bombardment within the ionization region and then separated according to mass-to-charge ratio. Indications of the magnitudes of the constituents of the gases are obtained as the ion currents representing each of the mass-to-charge ratios are selectively measured upon a current responsive measuring instrument 11. The various means for collecting and selectively measuring the ion currents are shown and described in the aforementioned patents relating to alternative forms of mass spectrometer apparatus.

As has been mentioned heretofore, the sensitivity of mass spectrometer apparatus as commonly employed has been found to vary with changes in the pressure within sample reservoir 8, the speed of evacuation, the ultimate pressure and the flow conductances of the apparatus. The reasons for this will be apparent from the following derivations of the flow relationships.

Assume that equilibrium conditions for a given sample analysis have been reached within the described apparatus of Fig. 1. Then

$$N_L = N_P$$

(1)

where N_L is the number of molecules per unit time entering through leak 9 and N_P is the number of molecules per unit time exhausting through diffusion pump 3 and rough pump 4. Now, if F_L is the equivalent flow conductance of tubular connection 10 including leak 9 and S_P is the speed of evacuation (or conductance) of the vacuum pumping system at the juncture of pump connection 2 with tube 1 (neglecting any pressure differential within tube 1), we may write

$$F_L(n-n_1) = S_P(n_1-n_u) \quad (2)$$

where n is the molecular density within the sample reservoir 8, n_1 is the molecular density at the place where ions are formed—in this case the same as the density within mass spectrometer tube 1, and n_u is the molecular density corresponding to the ultimate pressure P_u to which the mass spectrometer tube 1 can be evacuated under dynamic conditions. Solving Equation 2 for n_1 , we obtain

$$n_1 = \frac{(F_L n + S_P n_u)}{S_P + F_L} \quad (3)$$

In practice, S_P is usually of the order of liters per second while F_L is of the order of 10^{-5} or 10^{-4} liters per second, thus it may be stated that

$$S_P \gg F_L \quad (4)$$

whereby Equation 3 may be simplified to

$$n_1 = \frac{F_L}{S_P} n + n_u \quad (5)$$

We know, however, that at equilibrium conditions

$$n = \frac{P}{kT} \quad (6)$$

and that

$$n_u = \frac{P_u}{kT_1} \quad (6')$$

where P is the pressure within sample reservoir 8, k is Boltzman's constant, T is the temperature in degrees Kelvin of the gas entering leak 9 through tubular connection 10 and T_1 is the temperature in degrees Kelvin at which the molecules are ionized—in this case the same as the temperature within tube 1. Therefore, from Equations 5, 6 and 6', the following relation can be obtained:

$$n_1 = \left[\frac{F_L}{S_P} \frac{P}{T} + \frac{P_u}{kT_1} \right] \quad (7)$$

Within mass spectrometer tube 1 the number of ions formed per second is proportional to n_1 and also proportional to the ion current measured by instrument 11. Denoting these proportionality constants by C , it follows that the magnitude of the ion current measured by instrument 11 equals Cn_1 , whereby from Equation 7 we can write

$$Cn_1 = \frac{C}{k} \left[\frac{F_L P}{S_P T} + \frac{P_u}{kT_1} \right] \quad (8)$$

If the sensitivity of the mass spectrometer apparatus is defined, in accordance with the definition stated heretofore, as the ratio of the ion current measured by instrument 11 to the pressure P within sample reservoir 8, we obtain from Equation 8

$$\text{Sensitivity} = \frac{C}{k} \left[\frac{F_L}{S_P T} + \frac{P_u}{kT_1} \right] \quad (9)$$

Equation 9 shows clearly that the sensitivity of the described apparatus of Fig. 1 varies with changes in S_P , P_u and P . Thus, the characteristic changes in the pumping speed of diffusion pump 3—occurring from boiler temperature changes, alterations in the level of cooling medium 6, etc.—vary the sensitivity of the mass spectrometer. Similarly, a change in the pressure of the sample has the effect of altering the sensitivity of the apparatus.

According to the present invention, sensitivity variations are minimized or essentially eliminated by making the sensitivity of the mass spectrometer apparatus essentially independent of S_P and P_u over the operating range of pressure P . This is accomplished by inserting a constriction 12 between the region of ionization with

in mass spectrometer tube 1 and diffusion pump 3, and relating the flow conductance of the constriction to the remainder of the evacuation system in a manner which will be described presently. As illustrated in Fig. 1, constriction 12 can comprise a rotatable vane 13 mounted upon a shaft 14 within pump connection 2. Near one edge of vane 13 is attached a magnetic slug 15, the weight of which maintains vane 13 in a normally closed position. Vane 13 can be rotated into its open position by means of a solenoid 16 which is energized by a source of current 17 upon closure of a switch 18.

If the flow conductance of constriction 12 with vane 13 in its closed position is denoted as F_R , we may state for equilibrium conditions that

$$N_L = N_R = N_P \quad (10)$$

where N_R is the number of molecules per unit time passing through constriction 12. And, in a manner similar to the foregoing analysis, it follows that

$$F_L(n-n_1) = F_R(n_1-n_2) = S'_P(n_2-n_u) \quad (11)$$

where S'_P is the speed of evacuation or flow conductance measured at a plane traversing pump connection 2 between diffusion pump 3 and constriction 12 (neglecting any flow resistance between constriction 12 and the plane of measurement), and n_2 is the molecular density at such a plane. Observing that as a practical matter $S'_P \gg F_L$ and assuming that $F_R \gg F_L$, Equation 11 becomes

$$n_1 = \frac{F_L}{F_R} n + \frac{F_L}{S'_P} n + n_u \quad (12)$$

From the foregoing definition of sensitivity and Equation 12, we obtain

$$\text{Sensitivity} = \frac{C}{k} \left[\frac{F_L}{F_R T} + \frac{F_L}{S'_P T} + \frac{P_u}{kT_1} \right] \quad (13)$$

Now, with the proper adjustment of the flow conductances of leak 9 and constriction 12, the ratio F_L/F_R can be arranged such that over the desired operating range of the mass spectrometer apparatus

$$\frac{P_u}{kT_1} \ll \frac{F_L}{F_R T} \gg \frac{F_L}{S'_P T} \quad (14)$$

With this adjustment, Equation 13 reduces to approximately

$$\text{Sensitivity} = \frac{C}{kT} \left[\frac{F_L}{F_R} \right] \quad (15)$$

and the sensitivity becomes essentially independent of P , P_u and S'_P .

It may be further shown that

$$F_L = a \left[\frac{T}{M} \right]^{\frac{1}{2}} \quad (16)$$

and

$$F_L = b \left[\frac{T_1}{M} \right]^{\frac{1}{2}} \quad (17)$$

where a and b are geometrical constants and M is the mass of the constituents of the sample considered individually. Equation 15 may now be written as

$$\text{Sensitivity} = \frac{aC}{kb(T)^{\frac{1}{2}}(T_1)^{\frac{1}{2}}} \quad (18)$$

Equation 18 shows that the sensitivity of the mass spectrometer apparatus under these latter specified conditions according to the invention is independent of all the above mentioned factors except the temperature of the sample vapor or gas and the temperature within the mass spectrometer tube. If these temperatures are maintained at constant values, or are permitted to change only in such manner as always to satisfy Equation 18 for a given constant value of sensitivity, the sensitivity of the mass spectrometer apparatus does not vary for given geometrical configurations which result in F_L and F_R .

In order to assure constancy of temperature of the sample gas or vapor and within mass spectrometer tube 1, there is shown in Fig. 1 in simplified, schematic fashion an enclosure 19 of heat insulating material which is subdivided into sections 20 and 21. Heat is supplied to sample reservoir 8 and the portion of tubular connection

10 adjacent sample reservoir 8 by a current-carrying winding 22, wrapped around sample reservoir 8 in any convenient manner and energized from a source of current 23 through a variable resistor 24 and a disconnect switch 25. Similarly, heat is supplied to mass spectrometer tube 1 by means of a winding 26 which is energized from source 23 through switch 25 and a variable resistor 27. The temperature of sample reservoir 8 can be measured with a thermocouple 28 connected to a calibrated millivoltmeter 29, and the temperature of mass spectrometer tube 1 can be measured with a thermocouple 30 connected to a calibrated millivoltmeter 31. It is contemplated that a suitable automatic temperature regulating system can also be employed for the purpose of regulating the current through windings 22 and 26 and thus maintaining the temperatures of sample reservoir 8 and mass spectrometer tube 1 at desired constant or properly varying values. Furthermore, windings 22 and 26 need not be placed as illustrated around reservoir 8 and tube 1, respectively, but can be distributed around the interior of sections 20 and 21. Other well known forms of supplying heat to sections 20 and 21 can be employed alternatively to obtain the desired temperatures.

It is preferable that sample reservoir 8 and the portion of tubular connection 10 preceding leak 9 be maintained at essentially the same constant temperatures. If reservoir 8 and the portion of tubular connection 10 preceding leak 9 are at widely different temperatures, undesirable thermal diffusion and thermal transpiration effects may occur. Thermal diffusion results in a gas or vapor of lighter mass traveling toward the cool portion of the system faster than a gas or vapor of heavier mass, whereby the true proportions of light and heavy gas molecules in a sample are not measured. Thermal transpiration results from a temperature gradient and causes a pressure differential of gases or vapors having the same mass. Both of these effects are negligible if the temperature throughout the system including sample reservoir 8 and tube 1 is essentially the same. Of course, it will be understood that these effects are frequently of no substantial significance and, if little variation of the temperatures of sample reservoir 8 and tube 1 occurs during equilibrium conditions of operation, no heating or cooling means for reservoir 8 and tube 1 need be utilized to secure the desired constant sensitivity in accordance with the invention.

In the operation of the mass spectrometer apparatus of Fig. 1, sample reservoir 8 can be closed off from tube 1 by means of a suitable valve (not shown) inserted into tubular connection 10 between reservoir 8 and leak 9. Reservoir 8 is evacuated and a sample for analysis introduced thereto by means of a vacuum pump and sample supply arrangement, which has not been shown for the purpose of simplifying the drawing, connected to a tubulation 31'. An arrangement which can be employed for such purpose is shown and described in U. S. Patent No. 2,412,236, issued to Harold W. Washburn on December 10, 1946. The vane 13 is rotated to its open position and spectrometer tube 1 is exhausted by means of diffusion pump 3 and rough pump 4. Thereafter, vane 13 is rotated to its closed position and the sample gas or vapor is admitted to spectrometer tube 1 from reservoir 8 through leak 9. If the conditions as set forth above are observed, the sensitivity of the apparatus remains constant throughout the analysis of the sample.

It will be understood that the flow conductances of leak 9 and constriction 12 are arranged to fulfill the aforesaid conditions by constructing the openings therethrough such that the desired amount of resistance to flow is provided. In its closed position the vane 13 should not, of course, completely close off pumping connection 2 and, if necessary, a small hole (not shown) may be provided therein in order that the desired conductance F_R is supplied. The proper pumping speed $S'P$ can be obtained by the correct selection of the diffusion pump 3 and rough pump 4 along with the interconnections to spectrometer tube 1. The selection of these latter portions of the apparatus also serves in a large measure to determine the ultimate pressure to which the system can be evacuated. The required pressure within sample reservoir 8 can be arranged by the evacuation and admission of sample gas or vapor thereto. The pressure within spectrometer tube 1 is obtained as desired by the amount of sample gas or vapor admitted to the tube and the speed of the evacuation.

As a practical example, which can serve by way of illustration but not by limitation of the order of magnitude values for the various above-defined parameters, the following values have been found to provide constant sensitivity of mass spectrometer apparatus according to the invention:

$$\begin{aligned} F_L &\approx 10^{-4} \text{ liters/sec.} \\ F_R &\approx 0.2 \text{ liter/sec.} \\ S'P &\approx 10 \text{ liters/sec.} \\ T &\approx T_1 \\ P &\approx 10 \text{ microns} \\ P_u &\approx 5 \times 10^{-8} \text{ mm. Hg.} \end{aligned}$$

It is emphasized that these are order of magnitude values only and that such variations as fulfill the aforesaid equations are permissible to achieve the purpose of this invention. In the foregoing analysis the symbol " $>>$ " is intended to refer to a difference in magnitude between two parameters of at least 10. Reduction of such specified differences in magnitude much below a factor of 10 seriously affects the sensitivity stability of the mass spectrometer apparatus and renders the sensitivity response with sample pressure non-linear over the operating sample pressure range. The equations developed in the foregoing analysis are valid only in the molecular flow range, i. e., when the mean free path of the gas or vapor molecules is at least of the order of ten times the radius of the smallest aperture or orifice through which they must pass (see chapter 2 of "Scientific Foundations of Vacuum Technique" by Saul Dushman, Wiley and Sons, 1949).

In Fig. 2 there is shown an alternative form of constriction 12 which can be utilized in a vertically extending portion of pump connection 2. As shown this embodiment comprises a valve plate 32 which seats against an inwardly projecting flange 33 of pump connection 2. Attached to valve plate 32 is a valve stem 34 which extends slidably through bearings 35 and terminates in a magnetic slug 36. To raise the valve into its open position as illustrated by the dotted lines, a solenoid 37 may be energized from a suitable source of current (not shown). If insufficient leakage to provide the desired conductance F_R according to the invention does not occur when the valve is in its closed position, a small aperture 38 may be provided in valve plate 32.

It will be understood from the foregoing analysis that, in order to achieve constant sensitivity according to the invention, the constriction 12 need only be situated between the region of ionization of the molecules of the sample gas or vapor and the diffusion pump 3. In the forms of mass spectrometer tubes such as some of those mentioned heretofore wherein, it is either impossible or inconvenient to maintain the ionization region within a separate enclosure and at a substantially different pressure from the region in which the ions are separated according to mass-to-charge ratio, constriction 12 can be positioned within pump connection 2 as illustrated in Fig. 1. However, in mass spectrometer tubes wherein ionization can be performed within a chamber relatively isolated from the region of ion separation, e. g. tubes of the type disclosed in Joseph G. Neuland patent application Serial No. 61,627, filed November 23, 1948, and assigned to the assignee of the present invention, the constriction having the conductance F_R can be located within the mass spectrometer tube. A portion of a mass spectrometer tube of this latter type is shown in Fig. 3 wherein numerals employed heretofore are used to identify similar elements. In this tube gaseous samples are admitted through leak 9 and tubular connection 10 to an ionization chamber or region 40 which is separated from the remainder of the tube by a box-like structure 41. Within ionization chamber 40 there is positioned a thermionic filament 42 which, when energized from a source of current (not shown), emits electrons for the ionization by bombardment of the molecules of the sample. The ions thus produced are accelerated and focused through a series of suitably charged apertured electrodes 43 and directed into an analyzer tube 44 wherein they are separated according to mass-to-charge ratio. A more detailed description of this tube and the associated energizing equipment making up the complete mass spectrometer apparatus may be found in the aforesaid Neuland patent application. Mass spectrometer apparatus employing a similar type of tube is also shown and described in U. S. Patent No. 2,341,551, issued to Herbert Hoover, Jr., on February 15, 1944.

ance F_R , required to be supplied by a constriction according to the invention, is provided by an aperture 45 in conjunction with any additional passages from ionization chamber 40 into the mass spectrometer tube. The location of the constriction in this manner permits a higher pressure to be maintained within the ionization chamber than is maintained within the remainder of tube 1, whereby a shorter period of evacuation between sample analyses for any given mass spectrometer apparatus can be obtained. As illustrated in Fig. 3, the constriction supplying the conductance F_R may be fixed at a desired size in accordance with the above-specified relations and need not be obtained through the employment of a movable valve or vane as described in connection with Figs. 1 and 2. The temperature of the ionization region in the mass spectrometer tube of Fig. 3 can be maintained at a desired constant value by means of a furnace 46 which comprises a current carrying winding 47 around the exterior of the tube between two layers of asbestos tape 48. If desired, heat may be supplied to tubular connection 10 in a similar manner.

While the various direct current voltage supplies, high frequency oscillators, magnets, regulators, etc., which are necessary for the operation of the several types of mass spectrometer tubes referred to herein have not been shown and described in detail, it will be understood that these components are to be utilized as explained by the pertinent patent applications and patents denoted above. Furthermore, although various portions of the mass spectrometer tubes and the vacuum system interconnections of the figures of the drawings have been illustrated as being constructed of glass, it will be understood that other suitable material such as metal may be employed if desired. The measurement of the various pressures defined in the foregoing analysis can be accomplished through the use of conventional vacuum gages, e. g. the pressure within sample reservoir 8 can be measured with a McLeod gage or a micro-manometer and the pressure within the mass spectrometer tube may be measured with an ionization gage. Calculation and determination of the size of apertures or orifices to give the desired flow conductances required in the performance and utilization of the invention can be made as outlined by Saul Dushman in his aforementioned text (N. B. chapter 2). It should also be noted that the constriction 12 of Fig. 1 can be obtained by any suitable orifice of fixed dimensions, providing the above-specified necessary inter-relationships are satisfied.

While the invention has been described by reference to particular embodiments thereof, it will be understood that numerous changes may be made by those skilled in the art without actually departing from the invention. We, therefore, aim in the appended claims to cover all such equivalent variations as come within the true spirit and scope of the foregoing disclosure.

What we claim as new and desire to secure by Letters Patent of the United States is:

1. Mass spectrometer apparatus for sample analysis according to mass-to-charge ratio comprising a mass spectrometer tube including means for ionizing the molecule of a sample and means for separating and selectively measuring the ionized molecules according to mass-to-charge ratio, a sample inlet system for admitting samples at a pressure P and a temperature T to said mass spectrometer tube and having an equivalent flow conductance F_L , means for evacuating said mass spectrometer tube to an ultimate pressure P_u at a temperature T_1 including a vacuum pumping system connected to said mass spectrometer tube, a flow constriction disposed beyond said ionization means in the direction of flow and having a flow conductance F_R at least during the period of sample analysis, said evacuating means having a speed $S'P$ at a position in the direction of flow beyond said flow constriction, said flow conductances, pressures and evacuation speed having the following interrelationships:

$$S'P \gg F_L$$

$$F_R \gg F_L$$

$$\frac{P_u}{PT_1} \ll \frac{F_L}{F_R T} \gg \frac{F_L}{S'P T}$$

2. Apparatus as in claim 1 wherein said flow constriction includes a valve capable of being adjusted to have said flow conductance F_R .

3. Apparatus as in claim 1 wherein said flow constriction includes a member having at least one aperture of fixed dimensions.

4. Apparatus as in claim 2 wherein said valve is disposed in the connection of said evacuating means to said mass spectrometer tube.

5. Mass spectrometer apparatus for sample analysis according to mass-to-charge ratio comprising a mass spectrometer tube including means for ionizing the molecules of a sample and means for separating and selectively measuring the ionized molecules according to mass-to-charge ratio, a sample inlet system for admitting samples to said mass spectrometer tube at a pressure P and a temperature T including a sample reservoir connected to said mass spectrometer tube through a flow conductance F_L , means for evacuating said mass spectrometer tube to an ultimate pressure P_u at a temperature T_1 including a vacuum pumping system connected to said mass spectrometer tube, a flow constriction disposed beyond said ionization means in the direction of flow and having a flow conductance F_R at least during the period of sample analysis said evacuating means having a speed $S'P$ at a position in the direction of flow beyond said flow constriction, said flow conductances, pressures and evacuation speed having the following interrelationships:

$$S'P \gg F_L$$

$$F_R \gg F_L$$

$$\frac{P_u}{PT_1} \ll \frac{F_L}{F_R T} \gg \frac{F_L}{S'P T}$$

means for maintaining the connection of said sample reservoir to said mass spectrometer tube at a constant temperature, and means for maintaining at least the ionizing means of said mass spectrometer tube at a constant temperature.

6. Apparatus as in claim 5 in which the constant temperatures at which said sample reservoir connection and at least said ionizing means are maintained are essentially the same.

7. Mass spectrometer apparatus for sample analysis according to mass-to-charge ratio comprising a mass spectrometer tube including means for ionizing the molecules of a sample and means for separating and selectively measuring the ionized molecules according to mass-to-charge ratio, a sample inlet system for admitting samples to said mass spectrometer tube at a pressure P and a temperature T including a sample reservoir connected to said mass spectrometer tube through a flow conductance F_L , means for evacuating said mass spectrometer tube to an ultimate pressure P_u at a temperature T_1 including a vacuum pumping system connected to said mass spectrometer tube, a flow constriction disposed beyond said ionization means in the direction of flow and having a flow conductance F_R at least during the period of sample analysis, said evacuating means having a speed $S'P$ at a position in the direction of flow beyond said flow constriction, said flow conductances, pressures and evacuation speed having the following interrelationships:

$$S'P \gg F_L$$

$$F_R \gg F_L$$

$$\frac{P_u}{PT_1} \ll \frac{F_L}{F_R T} \gg \frac{F_L}{S'P T}$$

means for maintaining said sample reservoir and its interconnection to said mass spectrometer tube at a constant temperature, and means for maintaining said mass spectrometer tube at a constant temperature.

8. The method of separating a gaseous mixture into its constituent components in accordance with their mass to charge ratios which comprises introducing a sample of the gaseous mixture into a sample region, maintaining the mixture in the sample region at a desired sample region temperature and pressure, admitting the gaseous mixture from the sample region into an ionizing region undergoing continuous evacuation through an inlet having an inlet flow conductance, ionizing some of the gaseous mixture in an ionizing region, maintaining the gaseous mixture in the ionizing region at a desired ionizing region temperature, evacuating un-ionized molecules of the gaseous mixture at a predetermined speed of evacuation through an outlet

having an outlet flow conductance into a region having an ultimate evacuation pressure in a manner such that the speed of evacuation of the ionizing region and the outlet flow conductance are much greater than the inlet flow conductance and the ratio of the ultimate evacuation pressure to the product of the pressure of the gaseous mixture in the sample region times the temperature of the gaseous mixture in the ionizing region is much less than the ratio of the inlet flow conductance to the product of the outlet flow conductance times the temperature of the gaseous

mixture in the sample region and the last-mentioned ratio is much greater than the ratio of the inlet flow conductance to the product of the speed of evacuation of the ionizing region times the temperature of the gaseous mixture in the sample region, separating the ionized gaseous molecules in the ionizing region in accordance with their mass to charge ratios, and selectively collecting ions having a desired mass to charge ratio.
